(57) **CLAIM**

The ornamental design for a magnetic picture frame kit, as shown and described.

DESCRIPTION

The FIGURE is a front elevational view of a magnetic picture frame kit showing my new design.

The broken lines showing lettering and designs in FIG. 1 is for illustrative purposes only and forms no part of the claimed design.

The top, bottom and rear views, which are not shown, form no part of that which is claimed.

1 Claim, 1 Drawing Sheet

FIG. 1
